BOBBY PIN

Harold E. Chapin, San Fernando, and Robert S. Chapin, Oxnard, Calif.

Application March 4, 1950, Serial No. 147,698

20 Claims. (Cl. 132—51)

1

This invention relates to hairpins and deals more particularly with a bobby pin of efficient and novel form.

This application is a continuation-in-part of our pending applications, Serial No. 11,408, filed February 27, 1948, and Serial No. 30,100, filed May 29, 1948, both entitled Bobby Pin, and both now forfeited.

An object of the present invention is to provide a bobby pin that is readily and easily opened with one hand to receive hair, thereby obviating the faults in prior pins which entailed a two-handed operation, the undesirable use of the teeth of the user, or the need for other aids to open the same.

Another object of the invention is to provide a bobby pin that is readily opened with one hand and that will remain open for greater facility in applying the pin without danger of damage to fingernails and the fingers while being applied.

Another object of the invention is to provide a bobby pin that is effective to retain operative engagement with the hair and can be formed of stronger, more durable material than heretofore, since the construction embodies a power advantage enabling ready opening of the pin despite being formed of such stronger material.

A further object of the invention is to provide a bobby pin embodying the features above indicated and, in addition, being formed to prevent injury to the scalp in use and when being removed and also being formed to facilitate removal without snagging of the hair.

Another object of the invention is to provide a bobby pin, as indicated, that is roughened or knurled at the points of pressure application, to obviate inadvertent slippage while the same is being opened.

A further object of the invention is to provide a bobby pin of the character indicated that embodies means affording free non-snagging passage of hair during use, both when applying the bobby pin and removing the same.

Our invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawings merely show and the following description merely describes embodiments

2

of the present invention, which are given by way of illustration or example only.

In the drawings, like reference characters designate similar parts in the several views.

5 Fig. 1 is a top plan view of a preferred form of bobby pin according to the present invention.

Fig. 2 is a side view thereof in its normal closed hair-engaging position.

Fig. 3 is a similar view showing the pin open 10 and ready to receive a tress or lock of hair.

Fig. 4 is an enlarged fragmentary plan view showing an important structural detail.

Fig. 5 is a similarly enlarged cross-sectional view as taken on line 5—5 of Fig. 2.

15 Fig. 6 is a top plan view of a modified form of bobby pin according to the invention.

Figs. 7 and 8 are side views thereof, respectively closed and open, said views being comparable to Figs. 2 and 3, respectively.

20 Fig. 9 is a top plan view of a second modification.

Figs. 10 and 11 are side views thereof, respectively closed and open, as in the earlier forms of the invention.

25 Fig. 12 is a bottom plan view of said second modification.

Fig. 13 is a side view, in open condition, of a third modification of the invention.

Each of the four forms of the invention com- 30 prises, generally, an intermediate spring arm 15, an inner lever arm 16 connected by a relatively

small bend 17 to one end of arm 15, an outer arm 18 connected by a larger bend 19 to the other end of arm 15, latch shoulder means 20 provided intermediate the ends of outer arm 18 for latching engagement with the free end 21 of inner lever arm 16, and hair-guiding means 22 provided on arm 15 and operatively associated with said free end 21 to guide hair over said free end and to obviate hair slipping thereunder.

35 The arms 15, 16 and 18 that comprise the bobby pin are integrally formed of a length of flat-sectioned spring metal of the type usually employed for such articles. However, because of the power advantage embodied in the present structures, whereby the same are readily opened with one hand, said length of metal may have sturdier and longer-lasting properties that impart both durability and greater hair-gripping ability.

40 The arm 16 is arranged to be superimposed over portion 23 of arm 15 and to lie quite closely thereto. As seen in Fig. 2 of the preferred form, arm 16 and portion 23 are preferably spaced 45 somewhat to insure proper operative engagement

of the hair-guiding means 22 and end 21 of arm 16. Thus, in said preferred form, arm 16 and portion 23 are in spaced, substantially parallel, relationship. The hair-guiding means 22 is provided intermediate the ends of arm 15 and somewhat nearer bend 19 than bend 17. Arm 18 is arranged to be superimposed over that portion 24 of arm 15 that extends between bend 19 and hair-guiding means 15 and over arm 16, terminating at 25 short of bend 17.

The latch shoulder means 26 is preferably found in arm 8 to be intermediate its ends between a portion 26 that extends from bend 19 and a portion 27 that is superimposed over arm 16 and terminates at 25. As shown in the form of Figs. 6, 7 and 8, said portion 27 may be provided with crimps if the same are desired.

In the preferred form of the invention, the latch shoulder means 26 is formed as an outwardly directed dimple 28 that is so formed as to provide a shoulder wall 29 against which arm end 21 may be abutted when said end is disposed in the dimple. Inasmuch as the seat or cavity provided by the dimple resides entirely within the width of arm 18, said seat or cavity is relatively narrower than said width. Accordingly, arm end 21 is reduced in width, as best seen in Figs. 4 and 5, to freely enter the dimple to impinge on wall 29. In the modifications, latch shoulder means 26 comprises a shoulder wall 30 that is provided by upwardly offsetting arm portion 27 relative to arm portion 26. Shoulder walls 28 and 30 are alike in that the same each constitute an abutment for arm end 21.

In the preferred form, Figs. 1 to 5, the hair-guiding means 22 is formed as an outwardly directed dimple 31 that is somewhat deeper than dimple 28 and oppositely directed thereto. Dimple 31 affords an inwardly directed cavity 32 freely receptive of arm end 21. The latter is curved, substantially as shown, so that the point 33 thereof will reside in said cavity considerably below the lateral portions 34 flanking the cavity, thereby insuring that hair in the bight formed by arm portions 24 and 26, if moved in a direction away from bend 19, will be guided by said flanking portions and over the curvature of end 21 outwardly between arm 16 and arm portion 27.

In the modification of Figs. 6, 7 and 8, an inwardly directed hump 35 is formed in arm 15 instead of dimple 31, so that the same resides immediately adjacent to end 21 of arm 16. Said hump is formed as an offset return bend of a height at least equal to the thickness of arm 16. The hump thus guards end 21 and serves to guide hair thereover so as not to become snagged between arms 15 and 16. In this form of the invention, arm portion 26 is preferably provided with an offset hump 36 that accommodates hump 35 and thus allows arms 16 and 18 to contact each other to hold the thickness of the bobby pin to a minimum.

In the two other modifications, the hair-guiding means 22 comprises lateral portions 37 integrally formed on arm 15. These portions are upwardly bent to provide said arm with a U-shaped cross-section that houses arm end 21 substantially as shown. The upper edges 38 of portions 37 are at least flush with the upper face of arm 16 and preferably somewhat thereabove. The respective forward and rearward edges 39 and 40 are sloped or curved in the general manner shown. It will be evident that portions 37 serve to guide hair, moving as before, to prevent said hair snagging under arm end 21.

The bobby pin shown in Fig. 13, in addition to the above-described features, embodies a reversely bent arm 41 that extends from a sharp bend 42 at the end 21 of arm 6 along the top of the latter arm and beyond bend 17. The portions 37 are at least as high as the lower part of bend 42 to guide hair over said bend as before. The bend 1, in this form of the invention, may snag hair while the pin is being applied. Accordingly, ramps or sloping edges 43 on lateral portions 44 may be provided to obviate such hair snagging in a manner similar to the function of edges 46.

The normally closed pin, as in Figs. 2, 7 and 10, is adapted to be opened with one hand by applying the first and third fingers at the points indicated by arrows 45 and 46 and the thumb at the point indicated by arrow 47. Fig. 2 shows these arrows and it will be evident that the other forms afford the same points of pressure application. In Fig. 13, the point of pressure application indicated by arrow 46 is on the end 48 of arm 41. As shown in Figs. 9 and 12, these points of pressure may be roughened as by knurls 49, 50 and 51, respectively, to insure against inadvertent slippage of the pin while grasped by the fingers and thumb as indicated.

While arm 15 is preferably initially bowed, as shown in all of the forms, the entire pin may be generally straight, as in Fig. 10. However, in order to provide a more conforming, snugger fit against the curvature of the scalp in use, the entire pin is preferably initially bowed as in Figs. 2 and 7.

The closed pin is opened by pressing the fingers and thumb in the opposite directions indicated by arrows 45, 46 and 47 to flex and further bow arm 15. Such flexure brings the intermediate portion 52 of arm 15 against an intermediate portion of arm 16, thus pressing said latter arm upward and raising the end 21 thereof away from hair-guiding means 22 in a direction toward latch shoulder means 26. Such movement of arm end 21 will, therefore, snap the same into re-tension engagement with shoulder wall 29. The point 52 thus forms a fulcrum around which arm 16 pivots, the end 21 of said arm first upwardly flexing arm 18 and then latching onto means 26. This open condition of the pin is shown for each form in Figs. 3, 8, 11 and 13 in which, it will be seen, an open throat 53 is defined between arms 16 and 18.

The open pin may now be grasped by portions 24 and 26 and the open throat 53 moved toward the tress or lock of hair to be engaged by the pin. Said tress or lock of hair thus applies a pressure in the direction of arrow 54 to press arm end 21 out of latching engagement with latch shoulder means 26 to release the flexure of the pin arms and permit said arms to automatically close and thereby close arms 16 and 18 over. The pin can then be pressed endwise into place until bend 19 bears against the tress or lock, thus gripped. Thus, at least part of the tress or lock of hair is positioned in the bight 55 defined between arm portions 24 and 26 and, therefore, beyond arm end 21. Since said arm end is guarded by means 22, the pin can readily be removed by a simple pull on bend 19 or the arm parts adjacent thereto, since said means 22 will guide the hair over the arm end as hereinbefore indicated.

The term "superimposed," as employed in this description and in the appended claims, is intended to define general contiguity of the respec-

5.

tive arms 15, 16 and 18, whether or not they touch and regardless of whether one arm is above the other or alongside thereof.

While the invention that has been illustrated and described is now regarded as the preferred embodiment, the construction is, of course, subject to modifications without departing from the spirit and scope of the invention. It is therefore not desired to restrict the invention to the particular forms of construction illustrated and described, but to cover all modifications that may fall within the scope of the appended claims.

Having thus described the invention, what is claimed and desired to be secured by Letters Patent is:

1. A bobby pin comprising an integral length of spring material formed with an intermediate portion, a first portion bent back from one end of the intermediate portion and superimposed thereover, said first portion having a free end terminating at an intermediate part of the intermediate portion, hair-guiding means provided on said intermediate portion in operative association with said free end to guide hair over said free end, a second portion bent back from the other end of said intermediate portion and superimposed over the first portion, and latch shoulder means intermediate the ends of said second portion to receive and releasably hold the free end of the first portion.

2. The bobby pin according to claim 1: said length of material comprising flat-sectioned spring stock, and, the hair-guiding means comprising a dimple formed substantially centrally in the width of the intermediate arm, said dimple defining a cavity in which the mentioned free end of the first portion resides.

3. The bobby pin according to claim 1: said length of material comprising flat-sectioned spring stock, and, the latch shoulder means comprising a dimple formed substantially centrally in the width of the second portion, said dimple having a shoulder wall directed to be impinged by the mentioned free end of the first portion to hold the same releasably latched.

4. The bobby pin according to claim 1: said length of material comprising flat-sectioned spring stock, the hair-guiding means comprising a dimple formed substantially centrally in the width of the intermediate arm, said dimple defining a cavity in which the mentioned free end of the first portion resides, and the latch shoulder means comprising a dimple formed substantially centrally in the width of the second portion, said latter dimple having a shoulder wall directed to be impinged by the mentioned free end of the first portion to hold the same releasably latched.

5. A bobby pin that is adapted to be opened by one hand to receive hair and comprising a length of resilient material that is formed with two bends to define an intermediate portion, an inner portion extending from one bend and superimposed over the intermediate portion, an outer longer portion extending from the other bend and superimposed over the inner portion, hair-guiding means formed in the intermediate portion adjacent the free end of the inner portion, and latch shoulder means formed in the outer portion for receiving and releasably holding said free end upon flexure of the pin by the fingers of one hand against the inner and outer portions adjacent their bends in one direction and against an intermediate point of the intermediate portion in the opposite direction, where-

6.

by the latter point presses against the inner portion to urge the free end thereof to first outwardly flex the outer portion and then engage the latch shoulder means.

6. The bobby pin according to claim 5: the points of engagement of the fingers being roughened to obviate finger slippage during flexure of the bobby pin.

7. In a bobby pin, a resilient intermediate portion, two oppositely directed, resilient portions connected to the ends of the intermediate portion, said portions being arranged alongside each other with the free ends of the oppositely directed portions overlapping, the outer of the latter portions having a shoulder arranged to receive in latching engagement the free end of the innermost of said portions.

8. A bobby pin according to claim 7, in which the innermost of said portions is at least a little longer than the distance from said shoulder to the connection of the innermost portion with the intermediate portion, to permit latching engagement of the free end of the innermost portion with the shoulder when the overlapping free ends are moved outwardly from the intermediate portion.

9. In a bobby pin, a bowed, resilient, intermediate portion, two oppositely directed, resilient portions connected to the ends of the intermediate portion, said portions being arranged alongside each other with the free ends of the oppositely directed portions overlapping, the portions being arranged to move the overlapping portions outwardly by bowing the intermediate portion, the outer of the overlapping portions having means for receiving and releasably holding the free end of the inner portion when the overlapping free ends are moved outwardly by bowing of the intermediate portion.

10. A bobby pin comprising an integral length of resilient material providing an intermediate portion and two end, overlapping, portions, the overlapping portions being movable to a position in which the outer portion is under tension and arranged at an angle to the intermediate portion, and the inner, overlapping portion is disposed to brace and hold the outer portion in its said tensioned position, the inner and outer portions having inter-engaging means arranged to hold the latter portions in their said bracing and tensioned positions.

11. The bobby pin according to claim 1: the hair-guiding means comprising a hump formed in the intermediate portion adjacent to the free end of the first portion.

12. The bobby pin according to claim 5: the hair-guiding means comprising a hump formed in the intermediate portion.

13. The bobby pin according to claim 5: the latch shoulder means comprising an abutment wall.

14. A bobby pin according to claim 7: a hump in the intermediate portion and the inner of the oppositely directed portions extending approximately to said hump.

15. The bobby pin according to claim 1: a hump in the intermediate portion between its ends, the first portion having a free end terminating adjacent said hump, and the second portion having an end terminating substantially short of the opposite end of the bobby pin to expose a finger-rest part on the first portion to aid in flexing the bobby pin.

16. A bobby pin comprising a length of spring material formed with end bends to provide an

intermediate portion and two superimposed end portions superimposed on the intermediate portion, one end portion having an end terminating at an intermediate point of the intermediate portion, and hair-guiding means formed on said intermediate point to guide hair over said end.

17. The bobby pin according to claim 16: said hair-guiding means comprising portions of said intermediate point flanking said end substantially the thickness of the latter.

18. The bobby pin according to claim 16: said hair-guiding means comprising portions of said intermediate point flanking said end substantially the thickness of the latter end portion and having sloping edges to guide hair thereover. 15

19. The bobby pin according to claim 7: a re-

versely directed portion extending from a bend on the free end of the innermost of the resilient portions beyond the opposite end of said innermost portion.

20. The bobby pin according to claim 7: a re-versely directed portion extending from a bend on the free end of the innermost of the resilient portions beyond the opposite end of said innermost portion, and lateral portions on said re-versely directed portion and flanking said op-posite end of the innermost portion.
